Patented Aug. 30, 1910.

UNITED STATES PATENT OFFICE.

LEE D. HAMACHER AND CHARLES A. MELCHERT, OF KANSAS CITY, MISSOURI, AS
SIGNORS TO HAMACHER-HAWKINS MANUFACTURING CO., A CORPORATION OF
MISSOURI.

LOOSE-LEAF BOOK.

968,657.

Specification of Letters Patent. Patented Aug. 30, 1910.

Application filed December 30, 1907. Serial No. 408,507.

To all whom it may concern:

Be it known that we, LEE D. HAMACHER and CHARLES A. MELCHERT, citizens of the United States, residing at Kansas City, in 5 the county of Jackson and State of Missouri, have invented certain new and useful Improvements in Loose-Leaf Books, of which the following is a specification.

Our invention relates to improvements in 10 loose-leaf books; and our object is to provide a simple and inexpensive book of this character which is strong and durable, and well adapted for the purpose intended.

In order that the invention may be fully 15 understood, reference will now be made to the accompanying drawing, in which:

Figure 1 represents a broken end view of 20 a loose-leaf book embodying our invention. Fig. 2 is a vertical cross-section of same. Fig. 3 is a perspective of the metal parts of 25 the book ready to be assembled. Fig. 4 is a plan view of the metal parts assembled.

In carrying out the invention we employ 30 a frame 1, consisting of a back-plate 2 and vertical ends 3 provided with oppositely-disposed bearings 4.

5 and 6 designate two hook-carrying members having beaded outer edges 7 and 8, respectively, rockingly-mounted in the bearings 4. Members 5 and 6 are provided with 35 segmental hooks 9 and 10, respectively, the free ends of which interlock when the book is closed and thus limit said closing movement.

Member 5 has a channel 11 at its inner edge for the reception of a corrugated resilient member 12 and the inner edge of companion member 6, which extends into the channel and in conjunction with the sides 40 thereof forms a yielding hinge whereby the hook-carrying members are caused to operate in unison when the hooks are opened or closed. The inner edge of member 5 abuts against and partly compresses the resilient member, so that the latter will at all times 45 tend to force members 5 and 6 apart and thus reliably hold the hooks either in an open or a closed position.

Channel 11 is formed by a wall 13, an upper 50 lip 14, and a lower lip 15, which latter is somewhat wider than the former and extends well beneath member 6, so that it will contact with the underside thereof and thus limit the opening movement of the hooks 55 when members 5 and 6 are rocked upwardly.

The cover 16 of the book is secured to the back-plate by a piece of binding-cloth 17, which passes over the inner surface of said back-plate and is glued to the inner surface of the cover. Binding-cloth 17 is reliably 60 secured to the back-plate by a retaining-plate 18 having pieces 19 struck downwardly therefrom, which extend through registering openings in the back-plate and have their ends 20 upset against the underside 65 thereof.

When it is desired to insert or remove 70 loose-leaves from the rings, the latter are grasped near their interlocking ends and pulled open. This causes the hook-carrying 75 members to rock upwardly until lip 15 contacts with the underside of member 6, when further movement is stopped. The closing movement of the book is checked by the free ends of the hooks coming together.

Having thus described our invention, what 75 we claim is:

1. In a device of the character described, a back-plate having rigid upwardly-extending ends, two hook-carrying members rockingly-mounted in said ends, and a resilient member interposed between the hook-carrying members.

2. In a device of the character described, a back-plate having rigid upwardly-extending 85 ends each of which is provided with a pair of oppositely-disposed bearings, two hook-carrying members rockingly-mounted in said bearings, and a resilient member interposed between the hook-carrying members.

3. In a device of the character described, a frame, hook-carrying members rockingly-mounted therein having interlocking edges, and a corrugated resilient member interposed between said interlocking edges.

4. In a device of the character described, a frame, two hook-carrying members rockingly-mounted therein one of which has a channeled inner edge in which the inner 100 edge of the companion member fits, and a resilient member interposed between the inner wall of the channel and the inner edge of said companion member.

5. In a device of the character described, 105 a back-plate having upwardly-extending ends, two hook-carrying members rockingly-mounted in said ends, and a corrugated resilient member interposed between the hook-carrying members.

6. In a device of the character described, a back-plate, two hook-carrying members rockingly-mounted therein, lips and a wall forming a channel at the inner edge of one 20
- 5 of said members for the reception of the inner edge of the companion member, and a resilient member interposed between the wall of the channel and the inner edge of said companion member.
- 10 7. In a device of the character described, a frame, two hook-carrying members having interlocking inner edges and beaded outer edges which latter are rockingly-mounted in the frame, and resilient means engaging 25 the hook-carrying members, for the purpose described.
- 15 8. In a device of the character described,
- a frame, hook-carrying members rockingly-mounted therein, and a corrugated resilient member interposed between said hook-carrying members.
9. A device of the character described consisting of a frame, bearings at the ends thereof, hook-carrying members rockingly-mounted in said bearings having interlocking inner edges, and a resilient member interposed between said edges.

In testimony whereof we affix our signatures, in the presence of two witnesses.

LEE D. HAMACHER.

CHARLES A. MELCHERT.
